1919

UNITED STATES PATENT OFFICE.

LAVANDA M. ARMSTRONG, OF PEORIA, ILLINOIS, ASSIGNOR TO WM. J. H. STRONG, OF CHICAGO, ILLINOIS.

APPARATUS FOR SUPPLYING AIR TO OCCUPANTS OF AIRCRAFT.

Application filed July 9, 1919, Serial No. 309,772. Renewed March 14, 1924.

To all whom it may concern:

Be it known that I, LAVANDA M. ARMSTRONG, citizen of the United States, residing at Peoria, in the county of Peoria and State of Illinois, have invented certain new and useful Improvements in Apparatus for Supplying Air to Occupants of Aircraft; and I do hereby declare that the following is a full, clear, and exact description of the invention, which will enable others skilled in the art to which it appertains to make and use the same.

This invention relates to means for supplying air under pressure in a compartment serving as living quarters for persons when in high altitudes, and particularly for navigators and passengers of air craft or air vessels of every kind and character.

The main object of the invention is to provide for furnishing a supply of air to persons carried in air ships and air vessels of every kind, such air being placed under greater pressure than that of the surrounding air in high altitudes, and maintained in a compartment at a desired pressure automatically or partially so.

Besides the above objects, other objects and advantages are attainable all of which will appear herein aided by the accompanying drawing, it being understood that the invention is not confined to what is shown and described, as to the mechanism, since I have outlined but one manner of providing for the desired results.

Figure 1 shows one of the types of air craft to which my invention is applicable, part only of the invention being visible.

Figure 2 is a longitudinal section of a compartment of an air craft showing my invention.

Figure 3 is an elevation of a conventional form of barometer and connections extending therefrom as parts used with my invention.

Figure 4 is a plan of a valve and parts of an operating mechanism therefor.

Figure 5 is an elevation of the same, and

Figure 6 shows in perspective a suit for a navigator or other person, made air tight and adapted to be supplied with air under pressure.

The physical discomforts of persons in high or extremely high altitudes due to lack

of air pressure is well known. Because of this it is my purpose to provide an air tight compartment for all persons whether stationed on mountain tops or carried in air navigated by air craft, air being provided therein such as to furnish comfort almost, if not quite equal, to that at or near sea level.

Also, that where but one or two persons are navigating the air at high altitudes they may be provided each with a stout suit sufficiently large to permit air under pressure to surround the head and body, the air being supplied from any desired source, all of which will appear herein.

I believe it is entirely new to provide air for sustaining life in very high altitudes where the air is rare, compressing the air in a compartment by automatic means or by mechanism that may be controlled manually.

My invention is applicable to any form of air craft whether of the so-called lighter-than-air or heavier-than-air type.

For purposes of illustration the numeral 1 is indicative of an air craft of the lighter-than-air dirigible type, 2 denoting a car or gondola carried thereby, which for the purposes of my invention is so constructed as to be made air tight when desired. That is to say, the windows 3 thereof are of a form that will constitute air tight closures, the structure of the walls of the car, which is what I shall term the compartment, being such as to withstand internal air pressure.

4 is a valve of the safety or "pop" type located at any convenient point in one of the walls arranged to open outwardly for escape of excess pressure, the said valve being governed by a spring 4', for example.

In the forward wall of the compartment pointing in the direction of travel is a funnel shaped member 4², the walls of which flare to the proper degree and said member may be of a desired depth for gathering and compressing air within the compartment with which said member communicates.

Said member may be attached to the wall in any convenient manner as by means of 100 braces 5, for example, the tubular portion 6 extending through the wall of the compartment and having a valve-seat 6' terminating its end. But said member may be otherwise disposed with reference to the 105 wall carrying it.

7 is a hingedly mounted valve adapted to close upon the valve-seat 6.

8 is indicative of an air compressor situated in any convenient place connected 5 through a conduit 9 with the outer air preferably by way of the tubular portion 6 of said member 4², while 9 is a power delivering apparatus which for convenience may be an electric motor, for instance, belted or 10 otherwise connected in driving relation with the said air compressor.

10 shows a barometer of the ordinary mercurial J-form and 11 represents any 15 source of power, preferably one for producing electrical energy, such as a storage battery.

12 is a wire conduit connecting one pole of the said source of energy with one pole of the motor. 13 is a conduit connected to the 20 other pole of the battery and having contact permanently with the mercury of said barometer. 14 is a conduit connected at one end to the remaining pole of the motor and connected at its other end with the short or 25 open end of the barometer whereby, at times, it will have contact with the mercury as the same rises.

Said wire or conduit 14 is preferably adjustable so that contact thereof with the 30 mercury may be elective to close the circuit through the motor at any desired elevation, depending upon the rarity of the air encountered as will appear later.

As an example of the manner of permitting adjustment, 15 indicates a support for holding the conduit which may be slidable upon the barometer and secured in position thereon in any suitable manner, or the conduit may be held by friction in the support.

40 Again, the support may frictionally engage the portion on which it is mounted though the positive manner of holding the conduit is preferable.

While the air in the compartment of an 45 air craft at or near the sea level is at normal pressure, it cannot be normal at great elevations and therefore my purpose is to furnish an apparatus that will provide air pressure at any desired pressure within said 50 compartment and preferably in an automatic manner.

When in low altitudes, the valve 7 being open, the air is free to enter the compartment. But when reaching very altitudes 55 said valve at the proper time is to be closed preventing air, to be placed under pressure, from escaping.

The means for closing the valve may consist, as an example, of a lever 17 rigidly attached to the hinge portion of the valve, to which is pivoted, and from which extends, a rod 18 connected to one arm of a bell-crank 19 pivoted upon a suitable support such as a bracket 20 extending from the wall of 60 the compartment. Secured also to the wall

is a bracket 21 to which is pivoted, between its ends, a lever 22 one of whose ends engages the free arm of the bell-crank, the other end being free to move in a single given plane.

Rotatably mounted on a bracket 23 is a 70 wheel 24 belted to the driven wheel of the air compressor, for example, said wheel carrying a wrist pin 25 which in rotating with the same is moved against the lever 22 to swing it on its pivot and therethrough close 75 the valve. This action will appear more fully in the description of the operation. It is here to be pointed out that any other means for operating the valve may be resorted to, the means described being merely 80 an example of one manner of its accomplishment.

In traveling at considerable speed the air is gathered by the funnel and compressed in the compartment raising the pressure there- 85 in higher than the outer air, such pressure increasing in proportion to the increase in the speed of travel, and, incidently, the air at the same time is kept in circulation throughout the compartment, the pressure 90 maintained making for better physical comfort.

When, however, the altitude becomes such that the air pressure in the compartment is insufficient to yield the desired or required 95 comfort the valve 7 is closed and the air pressure in the compartment is increased by starting the compressor 8, the conduit 14 of the barometer having been previously ad- 100 justed to automatically accomplish this end. That is to say, it may be so adjusted that when reaching a previously determined height the electric circuit will be closed caused by the mercury rising in the open end of the tube due to decreasing air pres- 10 pressure. The circuit having been closed thus automatically, the motor is set in motion to operate the air compressor and simultane- 11 ously therewith the wrist pin 25 is moved against the lever 22 closing the valve. The compressor is kept in operation until the pressure is sufficient to cause the breaking of the circuit by driving the mercury column downward away from the conduit 14. Or, to constantly furnish fresh air to the com- 12 partment when a desired pressure is reached, the air-escape valve 4 may be permitted to leak air above that pressure. The valve 7 having been closed is held thus by the internal pressure.

In this manner comfort is established and maintained for the occupants.

Upon descending to lower levels said valve 7 may be manually opened to admit air, but if the external pressure is greater than the internal pressure the valve will open automatically and action of the compressor will automatically cease.

At any speed of travel air will be com- 13 pressed in the compartment due to the fun-

nel and it is clear that as the speed increases the pressure will become greater, but, as explained, the compressor is started automatically as the needs for more pressure become necessary.

Preferably the conduit 9 is connected with the tube of the funnel so that the compressor is aided in its work in that the more or less compression afforded by said funnel will give such compressor a more dense air for its work. However, the funnel may not be used. The operation of the balance of the mechanism does not depend upon it in any way.

15 Leading from the compartment is a valved conduit 28 by means of which air may be supplied to other compartments. Again, air may be supplied to a suit worn by any person whose duties require him to 20 work outside the compartment. In other words my invention in addition to the above purposes seeks to provide for any, such as navigators of aeroplanes, the same comfort as afforded by the closed compartment. 25 Where such a compartment would be too bulky, or undesirable, its equivalent may be furnished in a suit such as 26, Figure 6, including a head piece into which air can be introduced through a conduit 27 from any 30 suitable source such as the conduit 28, if the person is carried by a lighter-than-air machine, or from a pressure tank including therein a compressor, motor and battery as well as a barometer which would be outside 35 said tank, all acting or remaining idle according to the rarity or density of the air encountered, when carried by a heavier-than-air machine.

The head-piece may have an escape valve 0 of any well known or approved type at 27' to provide for escape of air above a certain pressure. This provides for air pressure for the body and head as well as to supply the lungs, it being required, of course, that the suit be of such construction as to withstand the internal pressure. The said tank (not shown) furnishes the equivalent of the compartment as will be understood.

1 The power means for operating the compressor may be any other arrangement. For example, any power delivery mechanism used in or about the craft whatever its type, even the propelling motor, which may be operatively connected with the compressor by any suitable means to accomplish the object sought.

1. In an air craft, the combination with a compartment capable of being made air tight, of means including a funnel through which to introduce air to said compartment

automatically in rarefied atmospheres in the travel of the craft against the air, and mechanism for automatically closing said funnel and introducing air into such compartment under still greater pressure than afforded by said funnel. 65

2. In an air craft, the combination with a compartment capable of being made air tight, of means in which to compress air 70 and through which to introduce the same to said compartment automatically in the travel of the craft against the air, a valve to close said means to the passage of air, and mechanism including an air compressor 75 set in motion automatically to close said valve and for introducing air into the compartment under still greater pressure.

3. In an air craft, the combination with a compartment capable of being made air 80 tight, of means for gathering and introducing air into the latter and to compress it therein by its travel against the air, a valve for closing said means, and mechanism to automatically close the valve including an 85 air compressor, power means to operate the same, and a member effected by the rarity or density of air adapted to automatically cause the starting and stopping of the compressor whereby to maintain air pressure in 90 said compartment at substantially a desired density.

4. In an air craft, the combination with a compartment capable of being made air tight, of means open to the outer air for 95 gathering and introducing air to the compartment under pressure, a valve to close said means, an air compressor, mechanism to close the valve including a motor, and a member effected by the density or rarity 100 of air adapted to set said mechanism in operation or terminate such operation.

5. In an air craft, the combination with a compartment capable of being made air-tight, of an air gathering device open to the outer air communicating with the interior of said compartment, a valve to close it, an air compressor including a conduit connected into said device between the valve and its open end, a motor for operating the 110 compressor, and a member effected by the variations in air pressure adapted to cause the motor to be started and stopped whereby the compressor will maintain air in the compartment at substantially a given density. 115

In testimony whereof I affix my signature in presence of two witnesses.
